UNITED STATES PATENT OFFICE.

BENJAMIN F. FOSS, OF FAIRFIELD, MAINE.

RADIATOR.

No. 879,953.

Specification of Letters Patent.

Patented Feb. 25, 1908.

Application filed April 22, 1907. Serial No. 369,642.

To all whom it may concern:

Be it known that I, BENJAMIN F. FOSS, a citizen of the United States, residing at Fairfield, in the county of Somerset and State of 5 Maine, have invented a new and useful Radiator, of which the following is a specification.

This invention relates to steam radiators, and more particularly to means whereby one or more portions of the radiator can be cut 10 off from the steam supply so as to reduce the amount of heating surface and correspondingly reduce the temperature of the room to be heated.

Another object of the invention is to provide 15 a simple and efficient form of valve which can be readily manipulated without danger of the parts becoming detached, all portions of the valve with the exception of its stem being concealed within the radiator.

With these and other objects in view the invention consists of certain novel features 20 of construction and combinations of parts which will be hereinafter more fully described and pointed out in the claims.

In the accompanying drawings is shown 25 the preferred form of the invention.

In said drawings: Figure 1 is a vertical longitudinal section through the lower portion of a steam radiator containing the present 30 improvements, one of the valves and its seat being shown in elevation; and Fig. 2 is an end view of one of the valves.

Referring to the figures by characters of reference, 1 designates a steam radiator 35 made up of a plurality of communicating sections as ordinarily and having an inlet 2 at one end while in the opposite end thereof is secured a tubular extension 3 interiorly screw threaded and designed to receive and 40 to be engaged by a threaded stem 4. Suitable means, such as a hand wheel 5, is secured to the outer end of this stem to facilitate the rotation thereof and formed upon the inner end of the stem is a head 6. As 45 shown in Fig. 1 the sections of the radiator communicate near their lower ends through openings 7 in the usual manner and the radiator is made up of three divisions each of which consists of one or more radiator sections. The sections communicate only at 50 their lower ends and communication is established between the divisions through externally screw threaded tubular members 8 which are inserted into the openings 7 between the divisions.

For the purpose of convenience in describ-

ing the invention one division of sections has been designated by the character A while the other divisions have been designated by the characters B and C respectively. Within 60 each of the tubular members 8 is fitted a tubular valve seat 9 and these seats are oppositely disposed so that one of them projects into the division A while the other projects into division C.

The head 6 is mounted to rotate within a socket 10 from which extends a screw threaded stem 11. A retaining ring 12 projects into the socket and serves to hold the head in position therein. Stem 11 is engaged by a 70 coupling sleeve 13 into which projects the threaded end of a spindle 14 which extends through the tubular members 8 and has an intermediate threaded portion 15 and a threaded end portion 16. Oppositely disposed valves 17 and 18 are secured upon the respective threaded portions, valve 17 being located in section C while valve 18 is located in section A and the two valves being oppositely disposed. Each of the valves is in the 75 form of a disk having a circular groove 19 in which is disposed a ring 20 of leather, rubber, or other suitable material, and said valve disk is held against displacement upon the threaded portion of the stem by means of 80 nuts 21 and 22. Each nut 22 has wings 23 radiating therefrom and disposed to travel within the seat 9 and support the adjoining valve in proper relation to the seat.

As has heretofore been stated the valves 90 17 and 18 are oppositely disposed. The distance between these valves is greater than the distance between the seats 9 so that by moving the spindle 14 in one direction both of the valves can be unseated and steam will 95 be free to pass from the inlet 2 through the two members 8 and into all of the radiator sections.

Should it be desired to reduce the heating 100 surface of the radiator the stem 4 is rotated in one direction so as to cause it to feed inward. The head 6 will rotate in socket 10 and spindle 14 will be pushed longitudinally without, however, rotating because of the contact of the valves or their wings 23 with 105 the members 8. Valve 17 will thus be pressed against its seat 9 and the supply of steam will be cut off from division C. By rotating the stem 4 in the opposite direction its head 6 will pull on the spindle 14 so as to 110 unseat valve 17 and seat valve 18. The two divisions B and C will therefore be cut off from

the inlet 2 and only the division A will be heated by the steam. By rotating stem 4 so as to unseat the valve 18 without however seating valve 17 the steam will be again free to pass into all the divisions of the radiator.

5 While the radiator has been described as sub-divided into groups it is to be understood that if preferred one section may constitute each group and by the word group it is not my intention to necessarily restrict myself to a plurality of sections.

10 It will be noted that a valve such as herein described permits the radiator to be easily controlled so as to regulate the amount of 15 heat radiated therefrom. Inasmuch as the valves do not rotate there is no danger of the parts becoming detached.

What is claimed is:

1. A radiator consisting of a plurality of 20 sections, valve seats at one end of the sections and through which said sections solely communicate, said sections being arranged to form an intermediate and end divisions, one of said end divisions having an inlet, and 25 connected simultaneously movable valves disposed to alternately close, said valves being designed to establish or cut off communication between the inlet division and either or both the remaining divisions.

30 2. A radiator comprising a plurality of

sections communicating solely at one end, said sections being arranged in an intermediate and end divisions, one of said end divisions having an inlet, valve seats interposed between the respective divisions, a spindle 35 extending through the seats, oppositely disposed valves thereon, and means extending from the radiator for actuating the spindle to alternately close the valves, and establish communication between the inlet division 40 and either or both the remaining divisions.

3. A radiator comprising a plurality of sections having registering openings at one end through which they communicate, valve seats disposed in certain of the openings and sub-dividing the radiator into an intermediate and end divisions, one of said end divisions having an inlet, a spindle movable longitudinally through the seats, oppositely disposed valves secured upon the spindle and 50 within the end divisions, and means for alternately seating and unseating the valves.

In testimony that I claim the foregoing as my own, I have hereto affixed my signature in the presence of two witnesses.

BENJAMIN F. FOSS.
